UNITED STATES PATENT OFFICE

102,385

DESIGN FOR A VEGETABLE SLICING MACHINE

Rudolph L. Marchfield, Chicago, Ill.

Application October 12, 1936, Serial No. 65,276

Term of patent 14 years

To all whom it may concern:

Be it known that I, Rudolph L. Marchfield, a citizen of the United States, residing at Chicago, in the county of Cook and State of Illinois, have invented a new, original, and ornamental Design for a Vegetable Slicing Machine, of which the following is a specification, reference being had to the accompanying drawing, forming part thereof.

Figure 1 is a side elevation of a vegetable slicing machine showing my new design.

Figure 2 is another side elevation thereof, taken at right angles to that shown in Figure 1.

Figure 3 is a top plan view thereof.

I claim:—

The ornamental design for a vegetable slicing machine as shown.

RUDOLPH L. MARCHFIELD.
